Patented May 7, 1918.

UNITED STATES PATENT OFFICE.

OTTO A. KNOPP, OF OAKLAND, CALIFORNIA.

ELECTRIC WATER-HEATER.

1,265,213.

Specification of Letters Patent.

Patented May 7, 1918.

Application filed June 7, 1916. Serial No. 102,223.

To all whom it may concern:

Be it known that I, OTTO A. KNOPP, a citizen of the United States, residing in the city of Oakland, county of Alameda, and State of California, have made a new and useful invention—to wit, Improvements in Electric Water-Heaters; and I do hereby declare the following to be a full, clear, concise, and exact description of the same.

10 Among the objects of this invention are to produce a thermostatic electric water heater of cheap and rugged construction without movable contacts and delicate resistance elements, so combined and arranged

15 that the heater will automatically reduce its wattage as soon as the desired water temperature is reached.

In this specification and the annexed drawings I illustrate the invention in the form 20 that I consider the best, but it is to be understood that I do not limit myself to this form because the invention may be embodied in other forms, and it is also to be understood that in and by the claims following the description, I desire to cover the invention in whatever form it may be embodied.

In the accompanying one sheet of drawings:

30 Figure 1 is a diagrammatic side elevation of a circulating reservoir of the kitchen boiler type having this invention applied thereto.

Fig. 2 is a longitudinal section of a water 35 heater constructed in accordance with this invention.

Fig. 3 is an enlarged fragmentary detail 40 of the automatic resilient control mechanism for regulating the compression on the resistance pile forming the heating element in the water heater.

Some of the particular advantages of this 45 invention as hereinafter described are as follows: The wattage is the highest during the initial heating period when the water is cold, and will automatically decrease as the temperature of the water rises. This decrease in wattage can be graduated in accordance with the temperature of water de-

50 sired by adjusting the automatic control, for example, when the water has reached the temperature of 120° Fahrenheit, or at any other desired point, the wattage automatically decreases gradually from this point until the minimum is reached. Inversely

55 the wattage will automatically rise again to

its maximum as soon as any amount of hot water is drawn from the boiler and replaced by cold water. Should the temperature of the water rise unduly high, due to impeded circulation or other causes, the wattage will be automatically cut down by the thermostatic action of the heater which decreases the wattage, which in consequence decreases the heat generated by the heating element, 60 protecting this element from an excessive temperature.

In detail the construction illustrated in the drawings includes the boiler 1 as generally used in domestic service, having the cold 70 water inlet pipe 2 extending well down into the boiler to near the bottom thereof. The hot water is drawn from the boiler through the service pipe 3 at the top thereof. The circulating system includes the cold water 75 outlet 4 leading from the bottom of the boiler through the water heater and into the outlet pipe 5 connecting with the service pipe 3 at or near the top of the boiler, whereby the thermo-siphon effect produced 80 by the water heater will cause the water within the boiler 1 to circulate, until the whole body reaches a uniform temperature, unless drawn off through the service pipe 3, in which event the hottest water from the 85 top of the boiler is forced into the service pipe by the incoming cold water introduced into the bottom of the boiler; such arrangement with modifications to meet particular conditions being in accordance with common 90 practice.

The heater includes the inclosing casing 6 preferably of cast iron, or the like, having the threaded hub 7 at the top to receive the outlet pipe 5, and a similar hub 8 at the bottom to receive the inlet pipe 4. The casing 6 is preferably sealed at the bottom by the removable ring 9 bolted thereto and compressing the heater base 10 against the flange 11 formed on the casing, thus rendering the 100 casing pressure tight. To prevent radiation of heat from the heater, it is surrounded with any suitable heat insulating material, such as mineral wool 12 inclosed within the ornamental jacket 13.

The heating unit includes the cylindrical shell 14 preferably of zinc or other material having a large temperature expansion coefficient, flanged at the bottom and soldered or otherwise hermetically fixed to the base 110 10 and closed at the top by the annular bushing 15 fixed therein.

The heating element consists of a pile of carbon disks 16, packed vertically on a glass rod or other insulating guide 17 fixed in the bottom contact 18 having a binding post 5 projecting through the base 10, from which it is suitably electrically insulated by an interposed gasket also forming a hermetic seal at this point, the terminal wire 19 is connected to the binding post by the nut 20 threaded thereon. The pile of disks are 10 mounted by the contact 21 resting thereon and held in position by the flexible conductor 22, held in position by the lock nuts 23-23 threaded on the top of the conducting post 24, insulated from and hermetically sealed to the base 10 at the bottom, and connected to the other terminal wire 25 of the electric circuit. The elasticity of the conductor 22 permits of the expansion of the 15 carbon disk pile in its separations.

The resistance and wattage consumption is regulated by varying the compression on the pile of carbon disks. This is accomplished by the knurled nut 26 threaded into 20 the bushing 15, and having a sleeve 27 fixed therein and inclosing a section of glass tube 28 resting on the contact 21 on top of the pile. Screwing down the nut 26 causes the glass tube to force the disks of the pile into 25 closer contact increasing the wattage and increasing the heat generated in the pile. The reverse action of the nut 26 having a reverse effect on the resistance. In this manner the normal resistance of the pile can be fixed 30 in accordance with the desired amount of heat to be generated in the pile, when the current is first turned on and the surrounding water is cold. The shell 14 is entirely filled with oil or some suitable nonelectrolytic liquid.

So far as I am aware, I am the first to surround or submerge such a resistance or compression heating element in oil or a non-electrolytic liquid. Such submersion results 45 in greater uniformity in the action of the pile, higher efficiency, greater durability, more rapid dissipation of heat therefrom and other electrical and mechanical advantages. The film of oil between the disks 50 forming the pile, prevents arcing and sparking therebetween, insures the positive and uniform separation between each and all of the disks under variation of mechanical pressure on the pile; whereas a pile of dry disks do not separate uniformly, or stick together in groups and others separating proportionately too far apart, set up arcing and 55 sparking that breaks down the opposed surfaces of the disks, destroying their usefulness and interfering with the uniform resistance of the pile as a whole, generating an overproduction of heat at a concentrated point when the generation of heat should be uniform throughout the pile.

60 In the present instance, oil is particularly

valuable as a dissipating agent conducting the heat from the pile to the shell 14, that in turn radiates the heat to the water passing through the casing 6. The shell 14 responding to the heat generated in it is expanded thereby, with the result that the longitudinal extension of the shell 14 proportionately releases the longitudinal compression placed on the resistance pile by the pressure of the glass tube 28 regulated by 70 the knurled nut 26, reducing the wattage consumption of the pile and diminishing the heat generated thereby. This action progresses until the water has reached the desired temperature, reducing the wattage to 75 the minimum, or cutting off the current entirely. This condition maintains until the water cools by radiation, or a quantity of hot water is drawn off through the service pipe 3, permitting a like quantity of cold 80 water to enter through the inlet pipe 2, which discharges near the bottom of the boiler replacing the hot water drawn from the casing 6, cooling the shell 14, causing it to contract and compress the resistance, 85 proportionately increasing the heat output therefrom until the high temperature of the water is again restored. Each variation of temperature in the body of water causes a consistent variation in the heat generated 90 and transmitted to the water by the heating unit.

There are instances where it is desirable to maintain the maximum wattage of the heater until a certain temperature of water 100 is reached, for instance, one hundred and twenty degrees. This is easily accomplished by introducing a resilient element between the adjusting nut and the top of the heating element, whereby a certain proportion 105 of the expansion of the shell 14 is compensated for by the contra-expansion in the resilient element, until the resilient element is overcome and the expansion of the shell 14 acts directly on the heating element. A 110 convenient means for accomplishing this object is illustrated in Fig. 3, in which the adjustable knurled nut 26' is threaded into a similarly adjustable annular nut 29 threaded in the bushing 15 and having an 115 inturned annular flange 30, clearing the diameter of the sleeve 27' which has an overhanging annular shoulder 31 adapted to engage the inturned flange 30. The calibrated spring 32 is compressed between the 120 shoulder 31 and the end of the adjusting nut 26' by the cap 33 threaded on the end of the sleeve 27', and bearing against the inturned flange 34 on the adjusting nut 26'. The cap 33 is provided with a screw driver slot 33' reached by removing the screw plug 35 in the top of the nut 26'. By this arrangement the spring 32 can be adjusted to resist the expansion of the carbon pile with 125 any desired initial tension. The tension of 130

the spring 32 can be regulated to hold the compression on the heating element, until the temperature of the water has risen to the desired degree, and the longitudinal extension of the shell 14 has progressed to a point where the flange 30 engages the shoulder 31, lifting the sleeve 27' and releasing the pressure on the heating element exerted through the rod 28', composed of some material that does not expand under heat, such as gamma steel. The temperature at which the compression of the heating pile is released is regulated by adjusting the nut 26' against the tension of the spring 32.

Having thus described my invention, what I claim and desire to secure by Letters Patent is:

1. An electric water heater including an inclosing expansive shell; a heating element in said shell; and means for varying the wattage of said element by the expansion and contraction of said shell.

2. An electric water heater including an inclosing expansive shell, a heating element in said shell; and a liquid in said shell submerging said element and means for varying the wattage of said element by the expansion and contraction of said shell.

3. An electric water heater including an inclosing casing having inlet and outlet openings; a hermetically sealed expansive shell in said casing; a thermostatic heating element in said shell; and means for varying the wattage of said element by the expansion and contraction of said shell.

4. An electric water heater including an

inclosing casing having inlet and outlet openings; a hermetically sealed expansive shell in said casing; a sectional heating element in said shell and compressed thereby, 40 whereby the expansion of said shell releases the compression on said element.

5. An electric water heater including an inclosing casing having inlet and outlet openings; a hermetically seated shell in 45 said casing; a thermostatic heating element in said shell, and a liquid in said shell.

6. An electric water heater including an inclosing casing having inlet and outlet openings; a hermetically sealed shell in said 50 casing; a compression heating element in said shell; and means in said shell for varying the compression on said element.

7. An electric water heater including an inclosing expansion shell; a compression 55 heating element in said shell, and a resilient compression means interposed between said shell and said heating element.

8. An electric water heater including an inclosing expansive shell; a compression 60 heating element in said shell; an adjustable compression means interposed between said shell and said heating element, and a resilient member interposed in said compression means.

In testimony whereof, I have hereunto set my hand at San Francisco, California, this 24th day of May, 1916.

OTTO A. KNOPP.

In presence of—

BALDWIN VALE,
A. J. HENRY.
